UNITED STATES PATENT OFFICE

109,388

DESIGN FOR A CAN OPENER

Herbert A. Berkman, Chicago, Ill., assignor to Zim Manufacturing Company, a corporation of Illinois

Application February 7, 1938, Serial No. 74,951

Term of patent 7 years

To all whom it may concern:

Be it known that I, Herbert A. Berkman, a citizen of the United States, residing in Chicago, in the county of Cook and State of Illinois, have invented a new, original, and ornamental Design for a Can Opener, of which the following is a specification, reference being had to the accompanying drawing, forming part thereof.

Figure 1 of the drawing is a side view of a can opener embodying my design; and Figs. 2 and 3 are, respectively, a top plan view and a bottom plan view of the can opener.

I claim:

The ornamental design for a can opener, as shown.

HERBERT A. BERKMAN.
